UNITED STATES PATENT OFFICE.

OTTO WEINSTEIN, OF BOSTON, MASSACHUSETTS, ASSIGNOR TO STANDARD NECKWEAR COMPANY, A CORPORATION OF MASSACHUSETTS.

NECKTIE.

Application filed March 25, 1926. Serial No. 97,400.

This invention relates to neckties, and to methods of making the same, and pertains particularly to an improvement in tubular ties.

- 5   The invention is directed toward providing a non-wrinkling, non-stretching tie, particularly of the four-in-hand type, and one which is not merely easy to manipulate, but strong and inexpensive to manufacture.
- 10   It has long been recognized that neckties normally require the presence of some supplementary material, in addition to the tie proper, in order that the knot shall have definiteness, smoothness, and proper size and shape. Heretofore, it has been the custom to provide liners for tubular ties, and which liners have usually been strips of fabric, felt, padding, and sometimes in order to avoid wrinkling, sheets of rubber have been used. Such fillers have been fitted in the tie, usually extending loosely, and often conforming to the shape of the tie. Sometimes the ends of the liner have been tacked down to the material of the tie by stitching with threads, this being done chiefly to position the liner endwise with respect to the casing. Liners have proved objectionable because they tend to twist, roll, wrinkle, and needlessly pad out the tie in the collar portion where it should be thin. As a result of rolling and twisting and any thickening locally, there results a correspondingly sharp wear on the face of the casing over the lump and ties thus wear out prematurely. Liners have proved expensive because of the cost of the material, the labor of cutting and shaping it, and inserting it in the casing. Nevertheless, liners have heretofore been considered a necessity.
- 40   The present invention is directed to the elimination of the liner, as such, as at present known. The invention provides a new necktie construction, wherein the casing is substantially homogeneously united with a reinforcing strip, which latter, for convenience, is defined as a "liner" or "tape". A unitary laminated structure results from this combination, and it possesses the desirable characteristics but none of the undesirable features of ties having the ordinary liner. By the present invention, the loose liner is dispensed with, thus saving in cost of liner material and labor of shaping it. The work of inserting the liner and stitching it in place is reduced.

Briefly described, the present invention provides an adhesive tape along the line of a seam on the interior of a tie casing. It is secured in place by heat and pressure, and it reinforces the seam and prevents the seam from opening up. By reason of the stiffness inherent to the tape, coupled with the unified three-ply laminated effect, provided by the tape, rubber cement and casing, it supplies the needed stiffening and cushioning or padded effect to the extent desirable in a necktie.

The above and other details and advantages are described and claimed in the following specification and claims, and the structure is illustrated in the accompanying drawing, in which:

Figure 1 represents a lengthwise view of a four-in-hand tie, illustrating the seam at the rear face of the tie and partly broken away to show the position of the gummed tape within the casing;

Figure 2 is a view of the gummed tape used in the casing shown in Figure 1;

Figure 3 is a sectional view through the gummed tape on the line 3—3 of Figure 2; and

Figure 4 is a sectional view on the line 4—4 of Figure 1, and enlarged showing the position of the gummed tape as united with the rear inner wall of the tie casing and bridging the seam, but with the edges of the tape well spaced from the edges of the tie.

Referring in detail to the drawing, Figure 1 shows the tubular casing of a necktie stretched out and broken away to indicate that it was longer than illustrated. The face of the tie is indicated at 1 and the rear of the tie is indicated at 2, as provided with the usual seam 3. In Figure 1, the raw or rough edges of the material of the tie at the seam portion are indicated at 4, as pressed back on either side of the seam. Ordinarily, the material of the casing is of such light construction that it makes no difference in which way the rough edges fall. In Figure 1, in the lower portion, the rear wall is broken away to show the position of the lengthwise supporting strip which serves as a binding element for the seam and which has a gummed surface 5 carried by a strip of tape 6. In the completed product, the gummed tape 6 bridges the seam and is secured to the inner rear wall 2 at either side 11

of the seam. It may be noted that the tape is narrower than the tie.

The inside of the front wall 1 is indicated at 1^a in Figure 1, where the front wall extends longer at both ends of the tie than the corresponding end edge 2^a of the rear wall 2.

In Figure 2 is illustrated the shape of the gummed tape used in the necktie in combination with the seam portion thereof. In

- 10 Figure 3, a cross sectional view of the tape is shown and it will be noted that there is a substantial thickness of gum material 5 on a supporting strip of suitable fabric which is preferably fairly stiff, at least sufficiently 15 so to maintain its full width and thus to resist wrinkling more than it would if its fabric was of extremely light gauzy material. Somewhat similar material has been used heretofore to assist in patching torn 20 places in cloth. The material is used by pressing with a hot iron, either on the surface of the tape or on the opposite side of the cloth to which the gummed surface of the tape is applied. The heat and pressure 25 soften the material of the gum composition and cause it to impregnate and adhere to the cloth. A similar principle is used in the present invention in incorporating the gummed tape with the rear side of the seam 30 of the necktie. The material of the fabric 6 should be relatively non-stretchable, because it takes the full strength of strain and stretch to which the tie is subjected.

- 35 In Figure 4, an enlarged cross sectional view is shown, and in this view, the unitary laminated effect is evident wherein the fabric of the tape 6 is held against the rear face of the casing and over the raw edge of the seam portion, by means of the rubber 40 composition adhesive material 5 which has now become practically a part of both the tape 6 and the casing wall 2 and the raw edges 4 of the casing wall.

- 45 In making up a tie involving the features of the present invention, a process is involved in the steps of using heat and pressure to combine the reinforcing strip 6 with the tie casing. Initially, after the seam is made, it is positioned centrally and the tie 50 is laid out flat with the seam uppermost. A strip of the tape 6 is placed at one end of the seam with the gummed portion next to the seam, and then a hot iron is applied to either the tape or to the opposite side of 55 the tie, and applied for the full length of the strip, causing the gum to soften and combine with the casing. Next the tie is reversed by drawing one end back through the casing so as to position the reinforcing strip and raw edge of the seam on the interior. The tie is now in saleable condition. 60 As a final step, the tie may again be pressed with a hot iron and with sufficient pressure to further incorporate the adhesive material 65 of the strip with the rear wall of the casing.

This is the last step prior to marketing the tie.

If desired, a stitching may be applied at 7 at each end of the strip, to tack it down to the rear wall of the casing in somewhat 70 the same manner as is frequently done for positioning the usual loose or sewn liners. In the present arrangement, the tacking 75 may assist in preventing the loosening of the end of the strip from the rear casing 75 wall, as might tend to occur after considerable use and as result of friction acting to roll or push the end of the gummed strip free from the cloth of the casing.

From the foregoing description, it will be 80 clear that there is no loose lining in this necktie which might twist, roll or wrinkle, and likewise that the invention dispenses with the usual liner which ordinarily must have a shape substantially the shape and 85 size of the contour of the tie in order to prevent it from becoming displaced from center to edge of the tie casing. The usual lining is eliminated. The cutting of the lining is dispensed with because a tape of 90 standard width can be used. The trouble of inserting a lining is avoided and the stitching of the lining is rendered unnecessary 95 because the usual pressing of the casing for the sake of appearance serves also to cause 95 the strip of tape to adhere to the casing in its proper position. Finally, it will be clear 100 that the present invention provides not only all of the necessary stiffening and padding at the points where needed, but it also accomplishes the reinforcing of the seam, a function not accomplished by a lining.

I claim:—

1. In a necktie, the combination with a tubular casing having a seam extending 105 lengthwise and on one face thereof, of a liner within said casing and comprising a strip of substantially non-stretchable material positioned over the seam and lengthwise thereof, and an intermediate layer of 110 an adhesive compound between said strip and said casing and adherent to both said strip and said casing and covering the entire surface of one face of said strip, said strip constituting the sole piece of cloth 115 within said casing.

2. In a necktie, the combination with a tubular casing having a seam extending lengthwise and on one face thereof, of a liner within said casing and comprising a 120 gummed tape covered with adhesive over all of one face thereof and more stiff than the material of the casing and positioned over the seam and lengthwise thereof and secured to the material of the casing throughout the length of the tape and over the entire surface of the tape by the adherence of the gummed surface.

3. In a necktie, the combination with a 125 tubular casing having front and rear walls

- and a seam lengthwise of the rear wall and substantially in the center thereof, of a reinforcing strip extending lengthwise within the casing and having its marginal edges terminating in spaced relation from the adjacent marginal edges of the tie casing and adherently secured to the rear wall of the casing and over the seam thereof at all points on the face of the tape, whereby the wall and the tape constitute a substantially unitary laminated structure throughout the surface of the tape.
4. In a necktie, the combination with a tubular casing having a seam lengthwise and on one face thereof of a liner within said casing and comprising a strip of substantially non-stretchable material positioned over the seam and lengthwise thereof and an intermediate layer of an adhesive material between said strip and said casing and adherent to both said strip and said casing and extending for substantially the full width of said strip whereby the strip is cemented to the casing, said strip constituting the sole piece of cloth within said casing.
5. In a necktie, the combination with a tubular casing of a liner within said casing and comprising a gummed tape more stiff than the material of the casing, and adhesive material on one face of said tape and substantially across the width of the tape and adherent to both said tape and said casing and constituting means uniting said tape to said casing substantially throughout the width of the tape.

In testimony whereof I affix my signature.
OTTO WEINSTEIN.
